(57) **CLAIM**

The ornamental design for a display panel of computer system with animated graphical user interface as shown.

DESCRIPTION

FIG. 1 is a front view of a first image of a first embodiment of a display panel of computer system with an animated graphical user interface;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of a first image of a second embodiment showing a display panel of computer system with animated graphical user interface;

FIG. 9 is a front view of a second image thereof;

FIG. 10 is a front view of a third image thereof;

FIG. 11 is a front view of a fourth image thereof;

FIG. 12 is a front view of a fifth image thereof; and,

FIG. 13 is a front view of a sixth image thereof.

The broken line showing of a display panel of computer system with an animated graphical user interface is included for the purpose of showing portions of the article which form no part of the claim.

The appearance of the transitional image sequentially transitions based on user input between the images shown in FIGS. 1-7. The environmental appearance of the transitional image sequentially transitions based on user input between the images shown in FIGS. 8-13. The process or period in which one image transitions to another forms no part of the claimed design.
